CLAIM

The ornamental design for a vehicle gear shifter, as shown and described.

DESCRIPTION

FIG. 1 is a perspective view of a first embodiment of a vehicle gear shifter with a park button in accordance with the present invention;

FIG. 2 is a perspective view of a second embodiment of a vehicle gear shifter, which is similar to the vehicle gear shifter of FIG. 1 with the park button removed; and,

FIG. 3 is a perspective view of a third embodiment of a vehicle gear shifter in accordance with the present invention.

The elements shown in phantom are for illustrative purposes only to disclose the environment related to the claimed design and do not form part of the claimed design.
